CLAIM

The ornamental design for a socks, as shown and described.

DESCRIPTION

FIG. 1 is a side elevational view of a sock showing my new design, the opposite side is a mirror image;

FIG. 2 is a bottom view thereof;

FIG. 3 is a side elevational view of a second embodiment of a sock showing my new design, the opposite side is a mirror image, the bottom is the same as FIG. 2;

FIG. 4 is a side elevational view of a third embodiment of a sock showing my new design, the opposite side is a mirror image;

FIG. 5 is a side elevational view of a fourth embodiment of a sock showing my new design, the opposite side is a mirror image; and,

FIG. 6 is a side elevational view of a fifth embodiment of a sock showing my new design, the opposite side is a mirror image.
